ELECTRONIC FADE-IN CONTROL SYSTEM
FOR PHONOGRAPHIC REPRODUCTION
OR THE LIKEJulius W. Buchholzer and Robert B. Drabenstott,
Akron, Ohio, assignors to The Summit Sound
Systems Company, Akron, Ohio, a corporation
of Ohio

Application October 4, 1946, Serial No. 701,130

10 Claims. (Cl. 179—100.1)

1

The present invention relates to a system for the electronic reproduction of sound generated by the usual phonograph disk and is designed to improve upon such systems so as to eliminate certain objectionable features ordinarily present when sound thus generated is transmitted to and reproduced over standard amplifier circuits.

While the invention has a wide range of utility and may be used for many purposes, the use to which the invention has been especially adapted is in the reproduction of records of organ or vocal music such as often played during funerals or other events where it is desirable to reproduce the records without the customary objectionable noises which have heretofore been necessarily present.

One of the objects of the invention is the elimination of the initial surface noise which is heard in phonographic reproductions as the needle travels over the spiral or lead-in portion of the sound track at the start of the reproduction. This is an important element of the system as the reproductions, especially at funerals, are conducted while the room is very still and every discordant sound is highly magnified to the ears of the auditors and unless the initial surface noise is entirely suppressed, the effect upon the auditors is very objectionable. The surface noise produced by the needle before it reaches the actual sound portion of the track will vary in intensity according to the material of the record or the extent to which it has been worn, and it is, therefore, one of the achievements of the present invention that however strong these noises may be they are completely suppressed so that no sound is reproduced until the needle reaches the first note of modulation on the record.

The principle upon which the first object of the invention is based is that the signals produced by the surface noises, although to the ear they may seem to be intense, are, in fact, relatively weak and in all practical cases are weaker than any sounds reproduced by the musical modulations. The system, therefore, provides a means which blocks off the passing of weak signals such as would be produced by surface sounds, but will clear at the first musical note.

Another object of the invention is to avoid a sudden transition from complete silence to the reproduction of musical sounds. If the musical notes were instantly produced at their full intensity, the impression would be highly objectionable. It is, therefore, one of the purposes of the invention to provide means by which the musical notes, as soon as they appear, are automatically

2

faded in from zero to the predetermined volume which is controlled by the gain setting of the audio system.

The accomplishment of the above specified objects creates a further condition which the present invention intends to rectify. It frequently happens that a pause or hiatus will occur in the flow of musical tones in a composition or vocal piece. At such a time occurring during the reproduction of the music, it is not desired that the musical notes again fade in, but that they should resume immediately at the full intensity determined by the setting of the audio system. The system which has been created, therefore, includes what may be termed a time delay which may be set at any suitable point so that operation of the fade-in is circumvented without interfering with passing the conventional audio signals through the amplifier. The duration of the time delay is selected so as to take care of the longest hiatus which may normally occur in selected records or compositions.

During such pauses as may occur when it is desirable to have the time delay function, the surface noises may appear, but the pauses are ordinarily of slight duration so that the ear does not catch them.

At the end of the musical notes, the blocking off of the surface noises will again take place and the complete reproduction will, therefore, be a perfect simulation of an actual musical performance without the objectionable noises which are usually present.

The invention is employed as an addition to any of the usual or well known audio amplifier circuits and is interposed between the phonographic reproducer and the amplifier circuit. It is not necessary to illustrate the amplifier circuit which is employed, as any well known arrangement may be adapted to the combination.

The drawing accompanying this application shows a control circuit which has been perfected for accomplishing the purposes of the invention and, as so designed, achieves the results which have been specified. It is not intended that the exact details be followed in every embodiment of the invention for the system may be altered or modified by one skilled in the art without in any way departing from the basic principles of the invention. On the drawings appear many figures which give values for resistances, condensers and the like, and these have been noted and are referred to herein as they give excellent results and will serve as a guide to one seeking to employ the invention, but they are not to be taken as

controlling. On the drawings also appear certain designations by which standard electronic units are known in the art, and these are given for the same purpose and with the same reservations.

Referring to the drawing and with particular reference to the means employed for suppressing the mechanical sounds which are caused by the tracking of the needle before the first note of modulation on the disk:

What is known in this art as a 1612 tube, indicated at 1, serves as a conventional input amplifier tube to any standard audio amplifier circuit through the lead 2. This tube is blocked off from passing a weak signal, such as is generated by the scratching noise from the needle, by a negative charge delivered to the control grid of the tube indicated at 3. This negative charge enters the system from a C-power supply at 4, thence through a 1 megohm resistor 5, through a switch 6 controlled by the relay 7. The negative charge is conducted by the line 8 through an additional 1 megohm resistor 9 to the grid 3. As the voltage supply passing to the grid 3 is negative when it appears on the grid 3, the gain of the tube is reduced to a negligible value and as long as the negative charge is at the grid, the tube will not pass any signals on to the next audio stage. The negative voltage supply is constant and the tube 1 cannot pass any signal until it is released by opening the switch 6.

A standard phonograph pickup is connected to the receptacle 12. The terminal marked 4 on the receptacle is connected to the line 13 having branches 13^a and 13^b. The conductors 13, 13^a and 13^b are shielded by a casing 14 from the receptacle 12 to the points where they enter the system.

As shown in the drawing, the line 13^a contains two 250M resistors 15 to ground. Between these resistors 15 is connected a line 16 which is, in turn, connected through a .05 coupling condenser to the signal grid 11 of the tube 1. The line 13^b is connected through a 100M resistor 17^a and a condenser 17^b to the grid 18 of the first triode section of a standard type 6SN7 tube indicated at 20. The plate opposed to the grid 18 is indicated at 19. It will thus be seen that as soon as a signal appears at the #4 terminal of the receptacle 12, it is simultaneously transmitted to the grids 11 and 18. The tube 20 is cascaded, as shown in the drawing, to provide two stages of resistance-coupled audio. The gain into the second section of this tube 20 is controlled by a variable 750M resistor indicated at 22.

As shown in the drawings, the resistor 22 is connected to the grid 24 of the second triode section of the tube 20. The plates 19 and 25 are connected to the B+ power line 28 through 510M and 250M resistors indicated at 19^a and 25^a, respectively. The signal output from the plate 25 of this section is fed by the line 26 through a condenser 27 into one cathode 29 of a type 6H6 tube 30 in which the audio frequency voltage is rectified. The corresponding plate element 31 of the tube 30 delivers a negative voltage to the line 33 which, in turn, delivers it to a switch terminal 37 and by the switch, to be described, to the three condensers 35 arranged in parallel and connected to three terminals 36^a, 36^b and 36^c of the variable time delay switch 40.

The line 33 is also connected to the grid 39 of a standard 6J5 tube indicated at 45 and to a 1 megohm resistor 38 to ground.

The 6J5 tube 45 is so biased that when there is no voltage (signal) appearing at the grid 39, the plate element 46 draws 6 milliamperes. The relay 7 heretofore referred to is connected in series with the plate 46, and when this amount of current, or slightly less, flows through the relay coil, the coil is sufficiently energized to close the switch 6. Closing the switch closes the circuit of the C-power supply which, as explained above, causes the negative charge to appear at the grid 3, suppressing any audio signal which may be transmitted to the grid and thus effectively shutting off the transmission of any signal from the tube 1 to the further elements of the audio amplifier.

As long as the signal received at the grids 11 and 13 is weak, as is characteristic of surface noise, it is insufficient to increase the bias at grid 39 of the tube 45 and, therefore, the switch 6 remains closed and the negative charge delivered by the line 8 and appearing at grid 3 suppresses the audio signal (surface noise) appearing at grid 11. When, however, the needle reaches the modulated portion of the groove on the record, the signal is sufficiently strong so that, passed by the tube 20 and amplified and rectified as explained, it appears as a negative voltage at the grid 39 of the tube 45. As soon as this negative voltage appears at grid 39, the increased bias causes the current from the plate 46 to drop, and as soon as this occurs, the energy in the relay 7 drops to a point where the switch 6 opens. Opening of the switch breaks the circuit of the C-supply to the grid 3 and the tube 1 then functions in the normal manner, passing the musical tones on to the remaining stages of the audio amplifier, by which these sounds are then reproduced and become audible.

It will be seen that the system, so far as has been described, insures that no audible sounds will be transmitted until the surface noise generated by the record is overcome by the louder musical tones. Thus is accomplished the first stated object of the invention, i. e., the suppression of objectionable noises caused by the scratching of the needle in the sound track prior to the first musical modulation thereon. This also suppresses the surface noise at the end of the record, after the time delay switch has ceased to function.

For accomplishing the second object of the invention, i. e., the fade in of the musical notes so that an abrupt commencement of the musical tones is avoided, the instrumentality designated at 50 and entitled "Fade in Speed" is provided.

Between the 1 megohm resistor 5 and the 1 megohm resistor 9, there is connected to the line 8 a line 52 which is connected to one terminal 53 of the fade-in-speed control element 50. Two additional terminals 54 and 55 are provided and the three terminals are connected in parallel through condensers 53^a, 54^a and 55^a to the line 57. These condensers are preferably .5 mf. paper condensers. The element 50 is provided with a rotary plate 60. In the position shown in the drawing, current diverted from the line 8 passes through the condenser 53^a only, but as the plate 60 is turned in clockwise direction the condenser capacity may be doubled or tripled. The line 57 is connected to the common ground.

As soon as the C-voltage passes through the switch 6, the condensers are charged; but when the main supply for the negative charge at grid 3 is broken by the opening of the switch 6, the

condensers discharge to ground through the resistance network indicated on the drawing which permits the residual negative charge to be removed from the grid 3 gradually so that the gain in the tube 1 is gradually increased, thus causing the intensity of the audio signal to gradually increase from zero to the predetermined intensity.

The speed at which the sound increases is, of course, dependent upon the capacity of the condensers, the slower the discharge rate to the ground, the slower is the fade in of the audio signal. The rotatable plate 60 permits the operator to govern the rate of fade in subject to the rated capacity of the condensers by cutting in one, two or more.

In order to prevent the recurrence of the fade in after the musical tones have started, in the event there is a pause in the record, the device designated as "Time Delay" and indicated by the numeral 40 is employed. This element of the system has already been referred to.

The element normally functions only after the switch 6 has been opened. The rotary plate 60 is shown with an enlarged portion in contact with the terminal 37 which leads to the grid 39 and also in contact with all three terminals 36^a, b and c, but one, two or all three of these terminals may be cut out, depending upon the extent to which the plate is moved between the stops 61. These condensers receive a negative charge while the musical tones are being transmitted through the tube 20, but when this is interrupted the voltage is gradually released to the system from the condensers, maintaining the rectified negative voltage during the pauses in the musical tones of the record. This prevents the relay from actuating the switch 6 and thus preserves the circuits as they were at the start of the musical tones. The time delay provision may be decreased or augmented within the capacity of the condensers 35 by turning the plate 61 to cut out one or more of the condensers.

The time delay switch is also intended to have a further function. A terminal 64 is provided at the time delay switch which is connected by the line 63 directly to the negative input line between the resistor 5 and switch 6. If the plate 60 is turned counterclockwise to the full extent permitted by the upper stop 61, it makes contact with the terminal 64 and the terminal 37, thus supplying a constant negative voltage to the grid 39. This causes the current from the plate 46 to drop off, which through the relay opens the switch 6 and the fade in is eliminated. This position of the time delay switch is used when it is desired to cut out the fade in altogether and will permit the system to pass conventional audio signals through the amplifier.

The connections which have not been described but are shown on the drawing are conventional. A standard milliammeter 72 is arranged to be plugged in to the jack 71 for the purpose of indicating the proper attract value and release value of the relay.

Other details and modifications may be suggested to those skilled in the art.

It will be seen that a system has been provided by which the sounds generated by the playing of a record may be reproduced electronically without the transmission of the usual surface noise that precedes the musical tones. This is due to the practical application of the fact that the intensity of such sounds is really less than the intensity of any of the musical tones, and by

maintaining a negative charge at the grid 3 of the 1612 tube until such time as the surface noise is drowned out by the first musical tone, the surface noise is completely blocked off from transmission through the audio amplifier. With this device is coupled and coordinated the fade-in control which avoids an abrupt commencement of the musical portion of the record. Further, the occurrence of an interruption in the record does not cause any difference in tone volume due to the holding function of the time delay switch. When, however, the time delay switch ceases to function after the termination of the modulated tones due to the discharge from the condensers 35, the negative charge will again appear at grid 3 of the tube 1 and the surface noise will be eliminated. The period involved is usually of such short duration that the surface noise does not affect the ear as it would at the start of the record.

The system shown and described herein is not limited to the specific purpose for which it has been described as it may be employed in the reproduction of broadcast transcriptions and for other duties in connection with electronic sound reproduction.

While, at many points in the foregoing, emphasis has been placed on the use of the above described system in the reproduction of musical records, it will be understood that the system shown herein will operate just as effectively in the case of a speaking record. Therefore, in the claims we have employed the term "modulated" to cover those portions of the record which may be either musical tones or any other tones which are found in the record and which are intended to be reproduced, thereby distinguishing from the surface noise which precedes the production intended to be reproduced.

40 What is claimed is:

1. In a system for electronic reproduction of a phonographic record, said system of the type having a phonographic reproducer and an audio amplifying system, means interposed between the phonographic reproducer and the audio amplifying system, said means comprising a source of negative charge connected to a control grid of a tube in the amplifying system, a make and break contact in series with said source, actuating means for said contact, electronic means energized by modulated impulses from said reproducer, and controlling said actuating means, and a delay device to maintain said contact in open condition during a hiatus in the modulated tones.

2. In a system for electronic reproduction of a phonographic record, said system of the type having a phonographic reproducer and an audio amplifying system, means interposed between the phonographic reproducer and the audio amplifying system, said means comprising a source of negative charge connected to a control grid of a tube in the amplifying system, a make and break contact in said source, actuating means for

60 said contact, electronic means energized by modulated impulses from said reproducer, and controlling said actuating means, and means operative when said contact is broken to cause a gradual increase in intensity of the transmission by the audio amplifying system.

3. In a system for electronic reproduction of a phonographic record, said system of the type having a phonographic reproducer and an audio amplifying system, means interposed between the phonographic reproducer and the audio ampli-

fying system, said means comprising a source of negative charge connected to a control grid of a tube in the amplifying system, a make and break contact in said source, actuating means for said contact, electronic means energized by modulated impulses from said reproducer, and controlling said actuating means, and a fade in control device operative when said contact is broken to release a negative charge at a gradual rate from the control grid.

4. In a system for electronic reproduction of phonographic records or the like, said system of the type having a phonographic reproducer and an audio amplifying system, a tube connected to the phonographic reproducer and constituting a unit of an audio amplifying system, said tube having a control grid, a constant source of negative voltage connected to the grid, a switch in series with said source, condenser means connected to the grid and said source, actuating means for said switch, electronic means energized by modulated impulses from said reproducer, and controlling said actuating means, said condenser means operating to release at a predetermined rate a negative charge from said grid after the switch is opened.

5. In a system for electronic reproduction of phonographic records or the like, said system of the type having a phonographic reproducer and an audio amplifying system, a tube connected to the phonographic reproducer and constituting a unit of an audio amplifying system, said tube having a control grid, a constant source of negative voltage connected to the grid, a switch in said source, condenser means connected in parallel to the grid and said source, actuating means for said switch, electronic means energized by modulated impulses from said reproducer, and controlling said actuating means, said condenser means operating to release at a predetermined rate a negative charge from said grid after the switch is opened, and a second condenser means connected to said electronic means and arranged to delay dissipation of charge therefrom, whereby said actuating means is not operated during a hiatus in the modulated pulses.

6. In a system for electronic reproduction of phonographic records or the like, said system of the type having an amplifier circuit, means normally impressing a negative charge on the grid of a tube in the amplifier circuit of said system sufficient to neutralize all signals at said tube, a switch controlling impressment of said charge, current-responsive actuating means for said switch, means comprising a thermionic tube with plate current controlling said actuating means and in sufficient amount to hold the said switch in position to retain said negative charge on the said grid, and electronic means connected to the input of said system and to the grid of said thermionic tube, and responsive to modulations in the input of said system above a predetermined volume level to bias the grid of said thermionic tube and thereby lower the plate current value thereof below said sufficient amount.

7. In a system for electronic reproduction of phonograph records or the like, said system of the type having an amplifier circuit, means normally impressing a negative charge on the grid of a tube in the amplifier circuit of said system sufficient to suppress all signals at said tube, a switch controlling impressment of said charge, current-responsive actuating means for said switch, a thermionic tube normally passing a current to said actuating means in sufficient

amount to hold the switch in grid-charge-retaining position, electronic means connected to the input of said system and to the grid of said thermionic tube, and responsive to modulations in the input of said system above a predetermined volume level, to lower the value of the said current below said sufficient amount, and means to retard dissipation of the said charge on the said grid on release of the switch.

10 8. In a system for electronic reproduction of phonograph records or the like, said system of the type having an amplifier circuit, means normally impressing a negative charge on the grid of a tube in the amplifier circuit of said system sufficient to suppress all signals at said tube, a switch controlling impressment of said charge, current-responsive actuating means for said switch, a thermionic tube normally passing a current to said actuating means in sufficient amount to hold the switch in grid-charge-retaining position, electronic means connected to the input of said system and to the grid of said thermionic tube, and responsive to modulations in the input of said system above a predetermined volume level, to lower the value of the said current below said sufficient amount, and means to retard dissipation of the said charge on the said grid on release of the switch, and means associated with the modulation-responsive means to retard restoration of said current to said sufficient amount during brief interruptions to the modulations in the system.

30 9. In a system for electronic reproduction of phonograph records or the like, said system of the type having an amplifier circuit, means normally impressing a negative charge on the grid of a tube in the amplifier circuit of said system sufficient to neutralize all signals at said tube, a switch controlling impressment of said charge, current-responsive actuating means for said switch, means comprising a thermionic tube with plate current leading to said actuating means, and in sufficient amount to hold the said switch in position to retain said negative charge on the said grid, electronic means connected to the input of said system and to the grid of said thermionic tube, and responsive to modulations in the input of said system above a predetermined volume level to bias the grid of said thermionic tube and thereby lower the plate current thereof below said sufficient amount, and means to retard dissipation of the negative charge on the first-mentioned grid on release of the switch.

40 10. In a system for electronic reproduction of phonograph records or the like, said system of the type having an amplifier circuit, means normally impressing a negative charge on the grid of a tube in the amplifier circuit of said system sufficient to neutralize all signals at said tube, a switch controlling impressment of said charge, current-responsive actuating means for said switch, means comprising a thermionic tube with plate current leading to said actuating means, and in sufficient amount to hold the said switch in position to retain said negative charge on said grid, electronic means connected to the input of said system and to the grid of said thermionic tube, and responsive to modulations in the input of said system above a predetermined volume level to bias the grid of said thermionic tube and thereby lower the plate current thereof below said sufficient amount, and means to retard dissipation of the negative charge on the first-mentioned grid on release of the switch, and means associated with the modulation-responsive means to retard

9

restoration of said current to said sufficient amount during brief interruptions to the modulations in the system.
